DESK COMPACT

Sebastien Roy, Jr., Arabi, La.

Application December 3, 1937, Serial No. 177,987

2 Claims. (Cl. 312—186)

This invention relates to what may be termed a "desk compact", the device being in the nature of a case or miniature cabinet for use upon a desk for holding writing materials, ink bottles, pens, pencils, and other material.

The invention has for its object, among others, to provide a device of this character which may be cheaply and economically constructed; will provide a convenient holder for writing instruments, and for holding letters, papers, and the like.

The invention together with its objects and advantages will be best understood from a study of the following description taken in connection with the accompanying drawings wherein:—

Figure 1 is a front elevational view of the device.

Figure 8 is a frequency distribution histogram showing the

Figure 2 is a fragmentary detail sectional view illustrating certain features of construction hereinafter more fully referred to, and which will

Figure 3 is a vertical sectional view through the device at about the center of the device with the device in complete open condition.

Figure 4 is a view similar to Figure 3 but taken nearer to one end of the device.

Figure 5 is a fragmentary top plan view showing a pocket for the reception of the post of a stamp

Figure 6 is an end elevational view of the post 30 forming part of the stamp rack, and

Figure 7 is a perspective view of a slide member hereinafter more fully referred to.

Referring to the drawings by reference numerals it will be seen that in the preferred embodiment thereof the case or compact comprises a bottom wall 5, end walls 6, top wall 7, front wall 8, and rear wall 9.

Walls 8 and 9 are hinged to the bottom wall 5 as at 10-10 for vertical swinging movement to opened and closed position.

The walls 6 and 9 are provided with suitable fastening elements 11 complementary to spring keeper elements 12 provided therefor on the top wall 7 at the front and rear edges of said wall.

45 Adjacent opposite ends thereof the case or compact is provided with vertical partitions 13 and horizontal partitions 14 forming with the end walls 6 and top wall 7 pigeon holes 15 in which are removably positioned shelves 16.

50 To support the shelves 16 the partitions 13 and end walls 6 are provided with grooves 17 that receive the edges of the shelves 16 in a manner to permit the shelves to be readily removed when it is desired to thoroughly clean the pigeon holes.

Between the pigeon holes 15 there is arranged a file-drawer 17 and the latter at opposite side edges thereof is provided with guide ribs 18 that are slidably accommodated on guide rails 19 suitably provided on the partitions 13 in slightly spaced relation to the top wall 1.

As shown in Figure 3 the drawer 17 is provided with a plurality of partitions 20 providing file spaces 21. For certain of the file spaces 21 there is provided an inclined false bottom 22, bottom 22 serving to facilitate the placing of envelopes and the like in the compartment. At the front end thereof the drawer 17 is provided with a knob 23.

Provided within the bottom of the case or compact, at each end thereof, are a pair of spaced guide rails 24—25 between which is secured a cross cleat 26 acting as a guide for a rod 27. On one end of the rod 27 is a crosshead 28 that has reduced end portions 29 working in guide slots 30 provided therefor in the rails 24, 25. The cross cleat 26 is provided with an aperture to accommodate the rod 27 and crosshead 28 is normally urged toward the front side of the case through the medium of a coil spring 31.

At the front side thereof the case accommodates between the rails of the respective pairs of rails 24, 25 ink wells 32, one of which may be used to contain ink of one color and the other of which may be used for containing ink of another color. The wells 32 are normally urged outwardly to a tilted or inclined position shown in Figures 3 and 4 through the medium of the spring-pressed crossheads 28, and to accommodate the wells 32 in the inclined position mentioned, and to serve to maintain the wells in such a position the front side or closure member 8 for the case is provided at the corners thereof adjacent the hinged edge of the member 8 with trays 33 that are suitably recessed as at 34 to accommodate the wells 32 in a manner best shown in Figure 4.

A blotter or other suitable absorbing pad 35 covers the inner face of the closure member 8. 40

Also carried by the closure member 8 is a combination rack 36.

Rack 36 comprises a pair of opposed laterally spaced rack bars 37 which are suitably notched as at 38 to accommodate pencils, pens, and the like, and at their inner ends the rack bars 37 are provided with hook-like formations 39 which serve to receive the pencils or pens on the rack 37 when the member 8 is swung upwardly to a closing position. 45 50

Also, pivotally supported between the forward ends of the bars 37 as at 40 is a tray 41 for receiving paper clips, rubber bands, etc.

As will be clear from a study of Figure 3 when the member 8 is swung vertically upwardly to a closed position the tray 41 will be accommodated within the case or compact forwardly of the drawer 17 while the wells, 32 against the action of the spring-pressed crosshead 28, will be forced inwardly of the case or compact between the rails 24, 25 of the respective pairs of rails.

The closure member 8, as previously explained, 10 is releasably secured in closed position through the medium of the complemental latch members 11, 12.

It will also be appreciated that with the member 9 in the position shown in Figure 3 access to 15 the case or compact at the rear side thereof may be had.

Also completing the assembly is a stamp rack indicated generally by the reference 41.

The rack 41 comprises a standard or post 42 to 20 which are secured, and from which extend laterally bars or arms 43 each of which is provided with a series of slots or notches 44 for accommodating the handle portions 45 of rubber stamps 46 as suggested in Figure 1.

25 At one end thereof the post 42 of the stamp rack is reduced and squared as at 47 to fit snugly within a complementarily shaped opening 48 provided therefor in the top wall 1 of the case. Also secured to the top wall 1 of the case is a 30 socket plate 49 that registers with the opening 48 and accommodates the lower end portion of the post 42 as clearly shown in Figure 3.

When not in use the rack 41 is accommodated within the case beneath the drawer 17 and compartment 15 and in this connection it will be 35 seen that the post 42 of the rack, when the latter is placed within the case, is accommodated between a pair of guide bars or cleats 47 suitably secured to the bottom wall 5 of the case and 40 extending from the front to the rear side of the case in slightly spaced relation and at opposite sides of the transverse center of the bottom wall 5.

Also, to prevent marring the polished surface 45 of the desk or other support on which the case is placed, the latter is provided with suitable feet or legs 48 of rubber or other suitable cushion material.

From the above it will be seen that I have provided a desk case or compact which will be found especially desirable for use in conjunction with flat top desks, serving as it does as a receptacle for pens, pencils, ink, as well as a file for letters, 5 cards, etc.

It is thought that a clear understanding of the construction, utility and advantages of an invention of this character will be had without a more detailed description.

Having thus described the invention what is 10 claimed as new is:—

1. A desk compact comprising a case having at opposite sides thereof hinged closure members whereby access to the case from either of said two sides may be had, said case being provided internally with shelf-equipped compartments and with a drawer slidably supported between said compartments, a pair of fixed guide bars mounted in the bottom of said case for slidably accommodating an inkwell between one end thereof, a spring-pressed slide operating between said guide bars and engageable with the ink-well for ejecting the same outwardly with respect to the case 15 incidental to a movement of one of said hinged members to an open position, and a stop element carried by said last-named hinged member to be engaged by the inkwell when moved outwardly of the casing.

2. A desk compact comprising a casing having 20 an open front, a closure member hinged on said casing for opening and closing the front thereof and adapted to assume a horizontal position when opened, a stop plate secured on said member and having a notch providing an inclined 25 face and a straight face, spaced guides in said casing to loosely receive therebetween an inkwell, a cross head mounted for a limited sliding movement on the guides to contact the inkwell, and spring means acting on the cross head to urge 30 the latter in a direction to slide the inkwell onto the stop plate and in engagement with the straight and inclined faces thereof on the closure member moving into an open position.
